UNITED STATES PATENT OFFICE

LEWIS R. HEIM, OF DANBURY, CONNECTICUT, ASSIGNOR, BY MESNE ASSIGNMENTS, TO CINCINNATI GRINDERS INCORPORATED, OF CINCINNATI, OHIO, A CORPORATION OF OHIO

GRINDING

Application filed October 22, 1923, Serial No. 669,899. Renewed March 12, 1929.

This invention relates to grinding and more particularly to the art and apparatus for grinding articles or bodies having a round or circular cross-section.

5 One of the objects of this invention is to provide apparatus for grinding bodies of round section that will be of simple and reliable action and of thoroughly practical, as well as rugged, construction. Another object is to provide apparatus of the above nature that will be of wide range of use and action and well adapted to meet not only the conditions of hard practical use, but also the varying and various requirements met with in practise. Another object of this invention is to provide grinding apparatus of the above nature capable of a high degree of uniformity as well as accuracy in its action and capable also of high speed of production of ground 10 articles without impairment of either accuracy or uniformity in result. Another object also is to provide a simple and thoroughly practical art of grinding articles of round section which may be inexpensively carried on 15 with accuracy and dependability of result. Other objects will be in part obvious or in part pointed out hereinafter.

The invention accordingly consists in the features of construction, combinations of elements, arrangements of parts and in the several steps and relation and order of each of the same to one or more of the others all as will be illustratively described herein, and the scope of the application of which will be indicated in the following claims.

In the accompanying drawings, in which is shown one of various possible embodiments of the mechanical features of this invention,

40 Figure 1 is a plan view of the grinding apparatus, certain parts being broken away to show certain features of construction more clearly,

45 Figure 2 is a rear view of the apparatus as seen from the bottom of Figure 1;

50 Figure 3 is a fragmentary sectional view as seen on the line 3—3 of Figure 2;

Figure 4 is a fragmentary sectional view of a portion of the reciprocating mechanism for reciprocating one of the wheels;

55 Figure 5 is a fragmentary view, partly in

section, as seen along the line 5—5 of Figure 2;

Figure 6 is a fragmentary view partly in section as seen along the line 6—6 of Figure 2; and

Figure 7 is a fragmentary elevation as seen along the line 7—7 of Figure 2,

Figure 8 is a side elevation of a work carrier, and more particularly is a fragmentary view as seen along the line 8—8 of Figure 1,

Figure 9 is a diagrammatic view in plan illustrating the action of the apparatus on articles of tapered form.

Figure 10 is a diagrammatic end view illustrating certain relations of the wheels and work supporting device.

Similar reference characters refer to similar parts throughout the several views of the drawings.

Referring now to the drawings and more particularly to Figures 1 and 2, there is shown at 10 a main supporting frame of any suitable construction and height, the frame 10 being shown broken away in Figure 2 at its lower portion and supported upon the upper part of the main frame 10 for slidable movement one toward the other, are the carriages 11 and 12, one adjacent each end of the main frame 10. The frame 10 is provided with suitable pairs of ways 13 and 14 extending longitudinally thereof for guiding the carriages 11 and 12 respectively lengthwise of the frame 10. At the adjacent ends of the carriages 11 and 12 are provided pairs of transversely spaced bearings 15 and 16 respectively adapted to rotatably support the shafts 17 and 18 respectively. The shaft 17 is provided with an elongated pulley 19 intermediate the bearings 15 and has mounted upon one over-hanging end thereof a grinding wheel 22. In Figure 1 the grinding wheel 22 is shown over-hanging the carriage 11 at the front side of the machine. The grinding wheel 22 is driven at a suitable grinding speed by means of a belt indicated in Figure 1 at 21, which makes connection with any suitable source of power and preferably to a pulley or other source of power within the main frame 10.

Upon one end of the shaft 18 is mounted

what will be hereinafter termed a regulating wheel 24, which wheel conveniently and preferably is made of a suitable abrasive material. The regulating wheel 24 is driven by means of a belt 20 running over the pulley 26 mounted upon the shaft 18 and intermediate of the bearings 16. The belt 20 is connected to any suitable source of power, preferably to a pulley or other source housed within the main frame 10.

The grinding wheel 22 and the regulating wheel 24 are rotated by means of their respective pulleys at speeds which are respectively high and low and in the directions indicated by the arrows in both Figures 1 and 2. The grinding wheel is thus made to present an operative surface traveling downwardly at high speed with respect to a work carrier 28 interposed between the two wheels and to be more clearly hereinafter described, and the regulating wheel 24 is thus made to present an operative surface which travels upwardly at a low speed with respect to the carrier 28. Preferably the regulating wheel 24, here shown as having a peripheral operative surface, is so related with respect to the work supporting surface of the carrier 28 that there exists between the path of travel of the operative surface of the regulating wheel 24 and the path of movement of the work along the carrier 28 an inclination which is effective to tend to urge the work along the carrier in the direction of the arrow 28^a in Figure 1. This relative inclination is preferably obtained by inclining the axis of rotation of the regulating wheel 24 in the vertical plane and may conveniently be brought about by making the bearing 16 adjacent the regulating wheel 24 of higher elevation than the bearing 16 remote from the regulating wheel 24. In this manner, the axis of the regulating wheel 24 is tilted out of the horizontal plane, and it may here be noted that a tilting of two or three degrees is effective to bring about a component or thrust on the part of the regulating wheel surface in the direction of the arrow 28^a with respect to the carrier 28. The regulating wheel 24 thus not only controls the rotation of the work on the carrier 28, but preferably also is effective to urge the work lengthwise of the carrier and in the direction of the arrow 28^a. This action will be made clearer hereinafter.

The above described relation between the regulating wheel 24, where the latter is operative by way of its peripheral surface, and the work carrier 28, is diagrammatically shown in Figure 10 in which the regulating wheel 24, the grinding wheel 22, and the work carrier 28 are diagrammatically shown as they would be seen as viewed from the right-hand end of Figure 1.

The wheels 22 and 24 are substantially enclosed in a protective casing 29 suitably se-

cured to the front part of the main frame 10 and of sufficient lateral and longitudinal expanse to permit of the adjustment and movement of the wheels as will be more clearly hereinafter described. This protective casing 29 is formed so as to provide a bridge portion 29^a at a point substantially intermediate of the two wheels and below their adjacent operative surfaces. This bridge portion 29^a is more clearly shown in Figure 8 of the drawings and it will be seen that it provides a substantially horizontally extending supporting surface upon which rests a frame member 30 (see Figures 1, 2 and 8) detachably held in place as by downwardly extending plate 31 and the cap screws 31^a passing therethrough and into the outer wall of the casing 29. The frame member 30 will be seen to extend between the two wheels and is formed to provide two vertically extending posts 30^a and 30^b, one on each side of the two wheels. These two spaced posts 30^a and 30^b support a work carrier 28 as by means of the bolts 30^c and 30^d, the posts 30^a and 30^b being slotted vertically (see Figures 2 and 8) to permit the making of a vertical adjustment of the carrier 28 with respect to the operative surfaces of the wheels.

It will be noted, however, that the carrier 28, in being thus supported adjacent its ends, may have its respective ends adjusted vertically independently of one another. Thus the carrier 28 may be given any desired degree of inclination with respect to the horizontal which may be demanded by the conditions of operation, and an example of which will be more particularly pointed out hereinafter.

As will be seen in Figure 2, the carrier 28 is preferably formed so that work positioned upon it, as indicated at 32, may partake of free lateral movement with respect to the carrier 28 itself; thus I prefer to give the carrier 28 substantially the form of a bar the upper surface 28^e, upon which the work rests, is inclined toward the operative surface of the regulating wheel 24. Thus work or articles of cylindrical form may be supplied successively or in succession to the carrier 28 for action thereon by the wheels. The regulating wheel 24, the path of travel of the operative surface of which is inclined with respect to the path of travel of the work along the carrier 28, will not only control the rotation of the work on the carrier 28, but also feed the work along in the direction of the arrow 28^a, all during the grinding action thereon by the grinding wheel 22. The inclined surface 28^e of the carrier 28 acts in effect to form a trough with the operative surface of the regulating wheel 24, thus not only insuring the retention of the work on the carrier, but also tending to make more effective the control of the rotation of the work 32 by the regulating wheel 24.

The above action takes place where the work operated upon is cylindrical throughout; it may hence be continuously or in succession fed along the carrier by the regulating wheel 24. When, however, it is desired to grind to a desired and uniform diameter work or articles which have a projecting irregularity at one end of the cylindrical portion thereof such as a bolt, for example, the work, of course, cannot be fed continuously through the apparatus. The work carrier 28, as hereinbefore described, is thus cut away or recessed at its front end or right hand end as viewed in Figure 8 as at 28^a so that the work 32, shown in Figure 8 as taking the form of a bolt, may have its headed or enlarged end accommodated in the recess of the carrier 28.

The carrier 28 has mounted upon it adjacent its rear end as viewed in Figure 1 or adjacent its left hand end as viewed in Figure 8, a stop member for limiting the movement of the work lengthwise of the carrier or in the direction of the arrow 28^a of Figure 1. This stop member may conveniently take the form of a relatively long screw 28^b (see Figure 8) extending longitudinally of the carrier 28 and in threaded engagement with a boss 28^c detachably secured to the carrier 28 in any suitable manner. The stop member thus formed by the screw 28^b may be moved lengthwise of itself so that its right hand end, against which the work 32 abuts, may be adjustably positioned at will. A lock nut 28^d may conveniently be employed to lock the screw 28^b in its adjusted position.

As shown in Figure 8, the stop screw 28^b limits the inner movement of the work 32 along the carrier 28 in a direction toward the left, the feeding component or thrust of the regulating wheel 24 in the direction of the arrow 28^a, and as hereinbefore clearly described, being effective to hold the work 32 securely against the stop. The grinding wheel 22 may thus perform the desired grinding action upon the cylindrical portion of the bolt 32 the stop preventing the entry of the head portion thereof between the two wheels.

Referring now to Figure 1, it may be seen that the regulating wheel 24 preferably of the type having a peripheral operative surface, has a broad operative face active adjacent the carrier 28. The regulating wheel 24 thus presents a controlling surface which is of sufficient expanse or extent lengthwise of the carrier 28 to effectively "back up" and support and control either a plurality of cylindrical articles arranged successively upon the carrier 28, as first hereinbefore set forth, or headed stock or work, such as bolts, of varying lengths when placed upon the carrier with the stop 28^b in position, as secondly hereinbefore set forth, during the grinding action of the grinding wheel 22. The latter, however, as will be seen in Figure 1 has an operative surface the width of which is materially less than the width of the surface of the regulating wheel. At this point it may be noted that for accuracy and uniformity in output of the apparatus, the wheels 22 and 24 must be trued periodically as by turning them down by means of a diamond, for example. One of the dominant aims of this invention is to provide a grinding apparatus in which the frequency of truing of the wheels will be reduced and in which a more uniform or equalized wear takes place in the wheels. The grinding wheel, traveling at the grinding speed and operating generally on hardened steel objects, is subjected to the greater wear, but non-uniformly in that its greatest wear takes place at that portion of the operative surface adjacent that end of the carrier from which the work enters the grip of the wheels.

Referring still to Figure 1, it will be seen that the shaft 17 of the grinding wheel 22 over-hangs the carriage 11 at the rear side of the apparatus and it may be noted that this shaft and the bearings 15 in which it is rotatably supported are so arranged that the shaft 17 with the wheel 22 may be given a movement in an axial direction with respect to the fixed bearings 15 on the carriage 11. Thus it will be noted that the driving pulley 19 on the shaft 17 is a broad faced pulley so that as the shaft 17 is moved upwardly as viewed in Figure 1 the driving connection through the belt 21 may be maintained throughout a material range of movement. The grinding wheel 22 may thus conveniently be given a movement lengthwise of the carrier 28. Preferably this movement is a reciprocatory movement and, where the work operated upon is cylindrical, and the work carrier 28 therefore arranged horizontally (or without inclination with respect to the path of travel of the surface of the grinding wheel) this movement of the grinding wheel 22 takes place in a direction substantially coincident with the tangent line of contact of the work on the carrier 28 with the grinding wheel 22. Thus, before describing in detail the mechanism for bringing about the movement of the grinding wheel, it may be noted that the grinding wheel 22 is reciprocated or moved lengthwise of the carrier 28 as the regulating wheel 24 rotates and feeds the work on the carrier, where the work takes the form of cylindrical articles such as rolls for roller bearings, or as the work is rotated and held against the stop 28^b by the regulating wheel 24 where the work takes the form of headed stock, such as the bolt 32 of Figure 8. As the grinding wheel 22 is reciprocated, it will be seen that first one end of its operative surface and then the other end begins the

grinding or cutting action, and thus uniformity of wear throughout the extent of the operative surface of the wheel is maintained.

The grinding wheel 22 advantageously takes the form of a cylindrical wheel having, thus, a peripheral operative surface, since its reciprocating movement relative to the work on the carrier may be more simply effected by bringing about a movement of the shaft 17 of the wheel 22 relative to the supporting bearings 15 thereof.

Considering now the mechanism for conveying to the grinding wheel 22 this movement, and referring more particularly to Figure 2, as well as to Figure 1, it will be seen that upon the one end of the shaft 18 upon which the regulating wheel 24 is supported, there is mounted a helical gear 33, which meshes with a helical gear 34 mounted upon a shaft 35 extending transversely of the regulating wheel shaft 18 and rotatably supported upon the rear side of the carriage 12. Thus the carriage 12 has mounted upon its rear side the spaced brackets 36 and 37 suitably formed to provide the bearings 38 and 39 respectively for rotatably supporting the shaft 35. At the left hand end of shaft 35, as viewed in both Figures 1 and 2, and preferably to the left of the helical gear 34 is mounted a gear 40 adapted to mesh with and drive a gear 41 rigidly mounted upon a shaft 42 rotatably supported in the bearing 43 conveniently formed in the bracket 36. The gears 42 and 41 may be proportioned one to another so as to obtain any desired speed ratio of the shaft 42 to the shaft 35, and as illustratively shown in Figure 2, the gears 42 and 41 bear such a relation to one another that the shaft 42 is driven at twice the speed of the shaft 35. In order to insure adequate support for the shaft 42, the left hand end thereof is supported in a bearing 44 formed in a bracket 45 and conveniently secured to the rear side of the main frame 10.

At the right hand end of the shaft 42, the latter carries a crank disk 46 (see Figures 2, 5 and 6) which is formed to provide a T-slot 47 extending centrally and transversely thereof. The T-slot 47 accommodates the head 48^a of a bolt 48, the outer or right hand end of which as seen in Figure 2, supports rotatably a roller 49. By this construction, as reference to Figure 6 will clearly show, the roller 49, forming in effect a crank-pin, may be adjustably positioned along the T-slot 47, to vary at will the distance of the roller 49 from the center of the crank disk 46 and hence to vary at will the throw of the crank-pin 49.

The bracket 36 is formed to provide also two aligned and spaced bearings 50 and 51 in which is supported for oscillation therein a shaft 52 extending longitudinally of the main frame 10 at the rear thereof and toward the grinding wheel end of the apparatus. The left hand end of the shaft 52, referring still

to Figure 2, is supported in the spaced bearings 53 and 54 formed in the lower end of a bracket 55 secured in any convenient manner, as by bolts, to the rear side of the grinding wheel carriage 11 (see also Figure 7). Between the spaced bearings 53 and 54 of the bracket 55 there is mounted upon the shaft 52 an upwardly extending arm 56, a key 57 locking the parts together so that whatever movement of the shaft 52 about its axis takes place is also conveyed to the arm 56. The key 57, however, coacts with a keyway 52^a extending lengthwise of the shaft 52, so that the operative relation above described between the shaft 52 and the arm 56 may be maintained irrespective of whatever relative movement may take place between these parts in the direction of the axis of the shaft 52.

Referring now to Figures 7 and 2, it will be noted that the rear end of the grinding wheel shaft 17 is reduced in section at its extreme end as at 17^a and upon this reduced end 17^a is positioned a yoke 58 having a downwardly extended arm 58^a connected to the upper end of the arm 56 through the link 59. The yoke 58 is relatively loosely mounted upon the reduced portion 17^a of the shaft 17 so as to permit free rotation of the latter therein, but is held against axial movement relative to the shaft 17 by means of a collar 60 rigidly secured to the extreme end of the shaft. A thrust bearing 61 of any suitable construction is interposed between the yoke 58 and the collar 60 and another thrust bearing 62 is interposed between the yoke 58 and the main portion of the shaft 17. By this construction, the shaft 17 may freely rotate with respect to the yoke 58 and it will be seen (see Figure 7) that an oscillation of the shaft 52 will, through the arm 56 and the link 59, move the shaft 17 and hence the grinding wheel 22 in an axial direction, the thrust bearings 61 and 62 acting to eliminate friction between the parts as well as to avoid binding therebetween.

The shaft 52 is swung about its axis to move the grinding wheel lengthwise of the work support 28 by means of the crank-pin or roller 49 hereinbefore described. The mechanism with which the crank-pin 49 coacts is conveniently and preferably mounted between the spaced bearings 50 and 51 and at the right hand end of the shaft 52 (see Figure 2). This mechanism comprises preferably a crank arm 63 (see Figures 2, 4 and 5) sleeved at its lower end as at 63^a to permit locking of the arm 63 to the shaft 52 as by means of the pins 52^b for example and to provide also an outer bearing surface for the lower end 64^a of an upwardly extending arm 64, the upper and left hand face of which is provided with a longitudinally extending slot 64^b within which the roller or crank-pin 49 engages. Thus, as the shaft 42 rotates the crank disk 46, the member 64 is made to oscillate about

the axis of the shaft 52, and if the member 64 is locked to the arm 63 (see Figure 4), the oscillating movement of the member 64 is communicated to the shaft 52 and hence to the grinding wheel 22 through the arm 63. Thus in Figure 4 is shown a clamping screw 65 for locking these members together.

Assuming that the member 64 is locked to the arm 63, the grinding wheel 22 will be reciprocated lengthwise of the carrier 28 throughout a stroke, the extent of which may be adjusted by adjustably positioning the follower or crank-pin 49 with respect to the crank disk 46. The regulating wheel 24, rotating at a materially slower speed than the grinding wheel 22, which latter wheel must be rotated at a sufficient speed to produce grinding action, thus forms a convenient and relatively low speed source of power for producing the traversing movement of the grinding wheel with respect to the operative surface of the regulating wheel 24. As the grinding wheel 22 is thus reciprocated, it will be noted that its motion throughout a given stroke is substantially simple harmonic in nature. This is advantageous inasmuch as the grinding wheel is thus given a greater speed of movement throughout substantially the middle part of its stroke and a lesser speed of travel at the ends of the stroke. Substantial uniformity of grinding action is thus assured, since the lesser portion of the grinding wheel effective on the work at the ends of the stroke is given more time to act upon the work.

Under certain conditions of operation, it may be desirable to bring the grinding wheel to a pause or to a position of momentary rest at the ends of its stroke, in order to compensate for the impossibility of reciprocating or moving the grinding wheel completely past the end of the work operated upon. This is particularly true where the work takes the form of headed stock, assumed hereinabove by way of example as the bolt 32 (see Figure 8). In order therefore to permit the above-mentioned action to take place, the clamping screw 65, (which as seen in Figure 4 is threaded into the member 64) passes through an arcuate slot 63^b in the arm 63 (see Figure 5). Hence, if the screw 65 is loosened sufficiently to unclamp the members 63 and 64, the resultant lost motion connection between the members 63 and 64 is effective to bring about a pause at the end of each oscillating movement of the arm 63 with the shaft 52. The arm 56 (see Figure 7) moving in unison with the shaft 52, will likewise be halted at the end of each oscillation with a resultant like action at the end of each stroke of the grinding wheel 22. The shortening of the stroke of the grinding wheel 22 resulting from the lost motion connection between the members 63 and 64 may be compensated for, if necessary, or brought back to the desired extent by ad-

justing the crank-pin 49 relative to the crank disk 46 (see Figure 6).

In order that the length of the pause at the end of the stroke of the grinding wheel may be adjusted, the length of the slot 63^b is made adjustable by means of the two oppositely mounted adjusting screws 63^c and 63^d threaded into the opposite ends of the arm 63 and having their end portions extending into the respective ends of the slot 63^b. Thus the amount of lost motion between the members 63 and 64 and hence the length of the interval of rest of the grinding wheel 22 may be adjusted at will.

It is to be noted that not only is the length of the stroke of the grinding wheel 22 lengthwise of the carrier 28 made adjustable so that it may be made commensurate with the length of the work, such as the bolt 32, operated upon, but also the position of the range of movement of the grinding wheel 22 may be exactly predetermined. Thus, the parts 63 and 64 (see Figures 4 and 5) may be clamped together in any desired relation of angular displacement therebetween, the locus of operation of the grinding wheel 22 being thus, for a given stroke, fixedly and exactly predetermined relative to the carrier or the work thereon. This same predetermined locus of operation of the grinding wheel 22 may be made also where the lost motion connection between the arm 63 and the crank operated member 64 is utilized, since it will be seen that, by reason of the adjusting screws 63^c and 63^d, the effective slot 63^b may in effect be not only lengthened or shortened, but also displaced with respect to the arm 63. It will thus be seen that the movement of the grinding wheel 22 may be accurately and precisely predetermined to meet the particular character or nature of the work operated upon.

At this point it may be noted that the grinding wheel 22 may be adjusted toward or away from the carrier 28 (or the regulating wheel 24) for the purpose, for example, of adjusting the apparatus for operation upon work of different diameters. A hand-wheel 66 (see Figure 1) operates a sleeve 67 which is in threaded engagement with the carriage 11 and is conveniently employed for adjustably positioning the carriage 11 with its associated grinding wheel 22 along the ways 13. As hereinbefore described and as particularly shown in Figure 2, it will be noted that, because of the splined connection between the shaft 52 and the grinding wheel moving arm 56, the grinding wheel may be given the desired reciprocating movements irrespective of its adjustment along the ways 13 with respect to the remaining parts of the apparatus.

As hereinbefore pointed out, the work, if of substantially uniform diameter or cylindrical throughout, may be supplied to the

carrier and fed successively by the action of the regulating wheel 24 through the apparatus. Where the work, however, is of non-uniform diameter, as for example when it takes the form of headed stock such as the bolt 32, a stop member such as the member 28^b (see Figure 8) must be employed to prevent the entry between the wheels of the enlarged or headed portion of the work. The work in the latter case must therefore be positioned between the wheels or fed thereto for action thereon and thereafter removed from the grip of the wheels at the conclusion of the grinding action thereon by the grinding wheel 22.

Considering now the manner in which work of the latter character is positioned on the carrier for action thereon by the wheels and thereafter removed therefrom, it will be noted, turning now to Figures 2 and 1, that the shaft 35 has splined thereon and intermediate of the bearings 38 and 39 a cylindrical cam 68 which, by reason of the splined connection to the shaft 35, indicated at 35^a (see also Figure 3) rotates with the shaft 35, but may slide with respect thereto. The cam 68 has a cam groove therein with which is adapted to coact a stationary roller or follower member 69 supported in the upper end of an arm 70 secured to the main frame 10 in a manner to be hereinafter more clearly described. The cam groove of the cam 68 is shaped to provide a major portion 68^a which, with respect to the axis of rotation of the cam 68, lies substantially in a plane transverse to this axis, and a minor portion 68^b which is displaced to the left (as viewed in Figure 2) of the plane of the major portion 68^a. The cam groove 68^a—68^b is of uniform width throughout so as to snugly receive the stationary follower or roller member 69, and it will thus be seen that, as the cam 68 rotates, the follower 69 will hold the cam 68 in fixed position throughout the coaction of the cam groove 68^a therewith, but will cause a movement to the right and a subsequent return movement to the left to take place during its coaction with the portion 68^b of the cam groove.

The shaft 35 is threaded throughout a substantial portion thereof intermediate the bearings 38 and 39 as is clearly shown in Figures 1 and 2. The cam 68 may be rigidly positioned, if desired, at any desired point along the shaft 35 by means of the nuts 71 and 72, one on each side of the cam 68 and in threaded engagement with the shaft 35. As shown in Figures 1 and 2, the nuts 71 and 72 lock the cam 68 rigidly against any slidable movement thereof along the shaft 35 hence, as the cam 68 is rotated and displaced as hereinabove described the shaft 35 together with the carriage 12 and the regulating wheel 24 is similarly displaced with respect to the stationary follower member 69. The right hand end of the shaft 35 has rigidly mounted there-

on the collars 35^b and 35^c between which and the bearing 39 are interposed the thrust bearings 73 and 74, in order that whatever thrusts in an axial direction of the shaft 35 take place may be effectively transmitted to, and taken up by, the carriage 12 to move the latter with the shaft 35.

Thus, assuming that the roller 69 is in coaction with the portion 68^b of the cam 68, the regulating wheel 24 is in withdrawn position with respect to the grinding wheel 22, so that the work 32 may be positioned on the carrier 28 (see Figure 8) and substantially against the stop member 28^b. As the regulating wheel 24 completes its movement to the left as viewed in Figures 1 or 2, the work 32, placed in rotation by the regulating wheel 24 is moved by the latter upwardly on the inclined supporting surface 28^c of the carrier 28 (see Figure 2) against the grinding wheel 22 for grinding action thereon. By this action the work is in effect gradually placed into coacting relation to the grinding wheel 22 for the commencement of the grinding, it being noted that the inclined supporting surface of the carrier is effective to insure the maintenance of contact of the work with the regulating wheel and the avoidance of contact thereof with the grinding wheel as the regulating wheel approaches its position of rest.

The portion 68^a of the cam 68 is effective to hold positively the regulating wheel 24 in this position of rest throughout the entire period of coaction of this portion 68^a with the followers 69. While the regulating wheel 24 is thus held in its position of rest, the reciprocation of the grinding wheel 22 as hereinbefore described takes place, it being noted that the number of complete cycles or reciprocations of the grinding wheel 22 may be made to depend upon the ratio of the gears 40 and 41 (see Figure 2). This ratio is illustratively shown as 2 to 1; hence the grinding wheel 22 commences and substantially completes four strokes lengthwise of the carrier 28 during the coaction of the stationary follower 69 with the portion 68^a of the groove of the cam 68.

As the portion 68^b of the cam groove comes into coaction with the follower 69 the grinding wheel 22 will be substantially completing one of its strokes, or may have come to a pause at the end of one of its strokes, and the carriage 12 with the regulating wheel 24 is withdrawn from the grinding wheel 22 and hence moved to the right. As soon as this movement begins, the work 32 is released from the grip of the two wheels, and it will be noted that the inclined surface 28^c of the carrier 28 is effective to urge the work toward the regulating wheel 24, thus keeping it out of contact with the grinding wheel 22. Preferably the extent of the withdrawing movement of the carriage 12 is such that the regulating wheel 24 opens up a sufficient gap

between itself and the carrier 28 to permit the work 32 to roll off of the carrier 28 and be thus discharged without manual handling from the apparatus. In this connection it might be noted that the inclined surface 28^a of the carrier 28 urges the work in effect to follow the regulating wheel 24 and also that the peripheral form of the regulating wheel 24 provides ample space below and adjacent to the carrier 28 to accommodate the falling or discharging work.

As the carriage 12 is moved to the left and returned to its initial position of rest, a new piece of work 32 may be placed upon the carrier 28, it being noted that the grinding wheel is either about to commence another stroke of movement or is still at rest during a pause at the end of a preceding stroke, depending upon the adjustment made as hereinbefore described. The operation is thereupon repeated.

It will be understood that the cam groove in the cam 68 is preferably shaped so as to provide a sufficiently great withdrawing movement of the regulating wheel 24 to effect the release of the work from the grip of the wheels. It will be understood, however, that under certain conditions it may be desirable to make this movement of such an extent as to permit the work 32 to drop between the wheel 24 and the work carrier 28. In order to prevent any jamming of the operative mechanism as the carriage 12 is withdrawn from or returned to its normal active position, the arm 70 in the upper end of which is supported the roller or cam follower member 69 is mounted at its lower end upon a stud 75 secured to the rear side of the main frame 10 as by the plate 75^a. As will be seen from Figure 2, the lower end of the arm 70 is sleeved as at 70^a so as to receive the stud 75, and the sleeved portion 70^a is slotted as at 70^b in order that the sleeved portion 70^a may be clamped not only adjustably with respect to the stud 75, but also with any desired degree of pressure as by the clamping screw 70^c (see also Figure 3). Thus, should the resistance to movement of the carriage 12 exceed a predetermined extent (dependent upon the pressure with which the sleeved portion 70^a is clamped) for any reason, the connection between the stud 75 and the arm 70 may yield to permit the otherwise stationary roller member 69 to be moved in response to the cam 68, thus relieving the driving mechanism from tending to overcome the excessive load imposed thereon by the carriage 12. Such action as above described may take place for example where a work piece may become lodged or positioned, by accident or otherwise, between the carrier 28 and the regulating wheel 24, as will be clearly understood by reference to Figure 2.

By means of the connection between the arm 70 and the stud 75 as hereinabove de-

scribed, the locus of operative movement of the carriage 12 and hence of the regulating wheel 24 may be predetermined at will. Thus for example, the arm 70 may be variously positioned about its pivotal supporting stud 75 to change the relation of the roller 69 with respect to the fixed part of the apparatus or main frame 10. This adjustment may be made use of in connection with the hand control or adjustment of the position of the regulating wheel to be more clearly hereinafter described, in order to accommodate the apparatus for different diameters of work operated upon. Preferably, however, and as hereinbefore briefly mentioned, the position of the cam 68 along the shaft 35, and hence relative to the carriage 12, is adjusted for this purpose by means of the nuts 71 and 72 one on each side of the cam 68.

The extent of the withdrawal movement of the regulating wheel 24 may be adjusted by backing the nut 72 away from the right hand end of the cam 68 to the desired degree. In Figures 1 and 2, the nut 72 is shown spaced from the cam 69 in the dotted line position 72^a as illustrative of such an adjustment. With the nut 72 thus backed away from the cam 68, the subsequent movement of the cam 68 in response to the coaction of the follower 69 with the portion 68^b of the cam groove is first a relative movement with respect to the shaft 35 (and hence with respect to the carriage 12) until the gap between the cam 68 and the nut 72 is taken up; thence follows the movement of the carriage 12 with the regulating wheel 24 to the right throughout the remainder of the throw of the cam groove. This adjustment is preferably utilized merely to release the work 32 from the grip of the wheels so that the work may be manually or otherwise removed from the carrier and replaced by the next piece of work to be operated upon.

The return movement of the carriage 12 to its normal operative position follows after the gap between the cam 68 and the collar 71 is closed by the first portion of the return movement of the cam 68. The work is thus placed in active operative relation to the two wheels, the reciprocating movement of the grinding wheel taking place as hereinbefore described, whereupon the withdrawal of the regulating wheel 24 and the subsequent operations above described are repeated.

It will also be noted that the nut 72 may be backed away from the right hand end of the cam 68 to interpose between it and the end of the cam a gap equal to or greater than the throw of the cam groove. When this adjustment is made, the cam 68 may freely move back and forth along the shaft 35, but, however, without conveying any movement to the carriage 12. The withdrawing movement of the regulating wheel 24 is thus eliminated, and the apparatus may thereupon function to

grind successively work which is of uniform diameter or cylindrical throughout, as hereinbefore described, it being understood that such work may be continuously fed in the direction of the arrow 28^a of Figure 1 through the apparatus. If, when the apparatus is thus adapted, it may be desired to eliminate the reciprocating movement of the grinding wheel 22 relative to the work on the carrier 28, the clamping screw 65 (see Figures 4 and 2) may be entirely removed, thus disconnecting the arm 64 from the arm 63. The former may thus freely oscillate in response to the crank-pin 49 without, however, transmitting its oscillating movement to the arm 63, which as hereinabove described, controls the movement of the grinding wheel 22 relative to the carrier 28 or the work thereon.

The regulating wheel 24, through the carriage 12, may be manually adjusted toward or away from the grinding wheel 22 by adjustably positioning the carriage 12 along the ways 14. In Figure 1 is shown a hand-wheel 76 rigidly connected to a shaft 77 preferably passing through the sleeve 67 and extending lengthwise of the apparatus. The shaft 77, which is housed within the main frame 10 is rotatably supported at its right hand end in a suitable bearing 78 mounted upon the interior of the main frame 10. The shaft 77, moreover, is held against axial movement thereof in any suitable manner. Adjacent its right hand end, the shaft 77 is threaded as at 77^a so as to be in threaded engagement with an interiorly threaded bushing 79 detachably connected to the carriage 12. Thus the bushing 79 is provided with an enlarged or headed portion 79^a at one end thereof and passes through a bracket 80 secured in any suitable manner to the underside of the carriage 12. The right hand end of the bushing 79 is exteriorly threaded and has in threaded engagement therewith a nut 79^b. The bushing 79 may thus be rigidly secured with respect to the bracket 80, the latter being clamped between the headed end 79^a and the nut 79^b of the bushing 79. Manual rotation of the shaft 77 by means of a hand-wheel 76 therefore causes a movement of the bushing 79 along the shaft 77, in a direction depending upon the direction in which the shaft 77 is rotated, and the bushing 79, being in rigid connection with the carriage 12, moves the latter with it.

This manual adjustment of the carriage 12 and hence of the regulating wheel 24 toward or away from the grinding wheel 22 may be made for example when the adjustment of the position of the carriage 12 with respect to the cam 68 is made, or for adjusting the relation of the regulating wheel with respect to the carrier or the grinding wheel 22 when the withdrawing mechanism of the regulating wheel is disconnected. When the withdrawing mechanism of the regulating wheel 24 is made operative, the nut 79^b of the bushing 79

is backed off as shown in Figure 1, so as to permit the cam member 68 to freely move the carriage 12, the bushing 79 being thus released from rigid connection with the bracket 82 of the carriage 12.

Referring now to Figures 1 and 2 there are generally indicated at 80 and 81 truing devices associated with the wheels 22 and 24 respectively and supported upon the carriages 11 and 12 respectively. These mechanisms may take the form for example as is shown in my co-pending application Serial No. 619,373, filed February 16, 1923, and are adapted to traverse a truing tool, such as a diamond relative to the operative surfaces of the two wheels. In grinding work of tapered form, the truing mechanism 81 may be employed to give the regulating wheel 24 a tapered form or shape shown in somewhat exaggerated form at 24^a in Figure 9, it being understood that this view is diagrammatic. The grinding wheel 22 is preferably maintained in a true cylindrical form, and in Figure 9 is shown at 22^a in dotted lines at the end of one of its strokes of movement.

The work, referring still to Figure 9, is shown at 32^a in the form of a tapered blank, and is supported upon the work carrier 28 with its one end abutting against the stop member 28^b, to prevent the work from wedging itself between the two wheels. The work carrier 28, however, is positioned so that an element of the conical surface of the work piece 32^a assumes substantial coincidence with the path of movement of the operative portion of the grinding wheel 22 relative to the work support itself. Thus, as is shown diagrammatically in Figure 9, it will be seen that the work carrier 28 assumes a position which may be said to be substantially coincident with the bisector of the angle between the adjacent operative surfaces of the two wheels. The carrier 28 may be thus positioned as by pivotally mounting the carrier frame, as at 82, to be adjustably swung about a vertical pivot.

The carrier 28 is also inclined with respect to the horizontal plane and has its front end (adjacent the supporting post 30^a) of lower elevation than the rear end thereof (adjacent the post 30^b). As hereinbefore described the independent supporting posts 30^a and 30^b of the carrier 28 permit each end of the carrier 28 to be adjustably displaced and positioned in both the vertical and the horizontal plane. Thus it will be seen that the apparatus may be readily accommodated for operation upon work of tapered form, as is diagrammatically shown in Figure 9, it being understood that the action of the remaining parts of the apparatus as hereinbefore in detail described may be efficiently and effectively utilized when acting upon work of this character. Reference to Figure 9 shows also that with work of tapered form, the grinding wheel 130

22 may be reciprocated beyond the ends of the work, where such action is desirable to insure more uniform wear of the grinding wheel and hence the maintenance of a continued uniformity in its action.

It will thus be seen that there has been provided by this invention a grinding apparatus and an art of grinding in which the several objects hereinbefore pointed out as well as many thoroughly practical advantages are successfully achieved. It will be noted that the apparatus is of practical and rugged construction throughout, is of great flexibility of action and operation and hence may be readily adapted to meet the various requirements of practical use. It will moreover be seen that the apparatus is of reliable and dependable action and moreover it is substantially fool-proof. It may also be pointed out that there has been provided in this invention an apparatus capable of high speed of production, and an art of grinding which may be carried on at high speed, all without impairment of accuracy and uniformity in result.

Certain features I have disclosed and claimed more broadly in my co-pending application Serial No. 669,693, filed October 20, 1923.

As many possible embodiments may be made of the mechanical features of the above invention and as the art herein described might be varied in various parts all without departing from the scope of the invention, it is to be understood that all matter herein set forth or shown in the accompanying drawings is to be interpreted as illustrative and not in a limiting sense.

I claim as my invention:

1. In apparatus of the character described, in combination, a carrier adapted to support thereon work of round section, a grinding wheel rotatable at relatively high speed and positioned on one side of said carrier, a regulating wheel on the other side of said carrier, means including a shaft rotated at relatively low speed for driving said regulating wheel to give the latter a slow surface speed, thereby to control the rotation of the work on said carrier, said wheels being adapted to present adjacent operative surfaces traveling in opposite directions, means driven from said slow speed shaft for giving said grinding wheel a linear movement in the general direction in which said work carrier extends, and means driven from said slow speed shaft for withdrawing one of said wheels from the other to release the work from the grip of said wheels.

2. In apparatus of the character described, in combination, a grinding wheel rotatable at relatively high speed, a regulating wheel, means for holding a work piece of round section between said wheels, means including a shaft rotated at relatively low speed for driv-

ing said regulating wheel to give the latter a slow surface speed, thereby to control the rotation of the work, and means driven from said slow speed shaft for withdrawing one of said wheels from the other to release the work from the grip of said wheels.

3. In apparatus of the character described, in combination, a carrier adapted to support for free lateral movement thereon work of round section, a grinding wheel on one side of said carrier and adapted to be rotated at relatively high speed, a regulating wheel on the other side of said carrier and adapted to be rotated at relatively low speed, said wheels being adapted to present adjacent operative surfaces traveling in opposite directions, and mechanism driven from said regulating wheel for withdrawing the regulating wheel from said grinding wheel to release the work therebetween.

4. In apparatus of the character described, in combination, a carrier adapted to support for free lateral movement thereon work of round section, a grinding wheel on one side of said carrier and adapted to be rotated at relatively high speed, a regulating wheel on the other side of said carrier and adapted to be rotated at relatively low speed, said wheels being adapted to present adjacent operative surfaces traveling in opposite directions,

means for predetermining the distance between the adjacent operative surfaces of said wheels to accommodate therebetween work of different diameter, automatic means for withdrawing one wheel from the other and from the work carrier to interpose between the withdrawn wheel and the work carrier a space through which the work may pass, and means for predetermining the extent of the withdrawing movement of the one wheel in order to accommodate said space to work of different diameters.

5. In apparatus of the character described, in combination, a carrier adapted to support thereon work of round section, a grinding wheel related to said carrier and rotatable at relatively high speed, a regulating wheel related to said carrier and rotatable at relatively low speed and in a direction to present an operative surface traveling in a direction relative to that of the grinding wheel surface to control the rotation of the work during the grinding operation thereon by said grinding wheel, means for giving said grinding wheel a reciprocating movement in a general direction lengthwise of said work carrier, means for withdrawing one of said wheels from the other to release the work from the grip of said wheels or to permit the insertion of work between said wheels, and means for causing said last-mentioned means to be operated in predetermined timed relation with respect to said means for reciprocating said grinding wheel.

6. In apparatus of the character described,

- in combination, a carrier adapted to support thereon work of round section, a grinding wheel related to said carrier and rotatable at relatively high speed, a regulating wheel related to said carrier and rotatable at relatively low speed and in a direction to present an operative surface traveling in a direction relative to that of the grinding wheel surface to control the rotation of the work during the 10 grinding operation thereon by said grinding wheel, and the path of travel of said regulating wheel being inclined with respect to the path of travel of work along said carrier, thereby to urge the work lengthwise of said 15 carrier, means for limiting the movement of the work lengthwise of said carrier, and means for withdrawing one of said wheels from the other to release the work from the grip of said wheels.
- 20 7. In apparatus of the character described, in combination, a grinding wheel rotatable at relatively high speed, a regulating wheel rotatable at relatively low speed and in a direction to present an operative surface 25 traveling in a direction relative to that of said grinding wheel surface to control the rotation of round work during grinding action thereon by said grinding wheel, a carrier extending between said wheels for supporting thereon work of round section, said carrier having a supporting surface inclined toward said regulating wheel, and means for withdrawing one of said wheels from the other to release the work from the 30 grip of said wheels, said inclined surface of said work carrier acting to cause the work when released to be urged toward said regulating wheel and out of contact with said grinding wheel.
- 35 8. In apparatus of the character described, in combination, a grinding wheel rotatable at relatively high speed, a regulating wheel rotatable at relatively low speed, said wheels being adapted to present adjacent operative 40 surfaces traveling in opposite directions, a carrier extending between said wheels for supporting thereon work of round section, said carrier having a supporting surface inclined toward said regulating wheel, the inclination of said supporting surface acting to increase the contact pressure between the work and said regulating wheel during normal action of said wheels on the work and acting to cause the work to roll toward the 45 regulating wheel when released from the grip of said wheels, and means for withdrawing said regulating wheel from said grinding wheel to release the work from the grip of said wheels.
- 50 9. In apparatus of the character described, in combination, a grinding wheel rotatable at relatively high speed, a regulating wheel rotatable at relatively low speed, said wheels being adapted to present adjacent operative 55 surfaces traveling in opposite directions, a carrier extending between said wheels for supporting thereon work of round section, said carrier having a supporting surface inclined toward said regulating wheel, and automatic means for withdrawing said regulating wheel from said carrier sufficiently to permit the work to pass between said carrier and said regulating wheel, the inclined supporting surface of said work carrier causing the work to roll off of the carrier.
- 60 10. In apparatus of the character described, in combination, a pair of abrasive wheels, means for holding work between and in operative relation to said wheels, power actuated means for moving one wheel relative to the other, and means adapted to yield upon said power actuated means being overloaded.
- 65 11. In apparatus of the character described, in combination, a pair of abrasive wheels, means for holding work between and in operative relation to said wheels, power actuated means adapted in recurring sequence to withdraw one of said wheels from the other and to return said wheel to its initial position, and means adapted to yield upon said power actuated means being overloaded.
- 70 12. In apparatus of the character described, in combination, a pair of abrasive wheels, means for holding work between and in operative relation to said wheels, a carriage rotatably supporting one of said wheels and adapted to be moved relative to the other of said wheels, a cam member and a follower member, one of which is associated with said carriage and the other of which is associated with a part which is fixed with respect to said carriage for bringing about a movement of said carriage relative to said other wheel, and means yieldably mounting one of said last mentioned members, said means being adapted to yield upon the resistance to movement of said carriage exceeding a predetermined extent.
- 75 13. In apparatus of the character described, in combination, a pair of abrasive wheels, means for holding work between and in operative relation to said wheels, a carriage rotatably supporting one of said wheels and adapted to be moved relative to the other of said wheels, a cam member and a follower member, one of which is associated with said carriage and the other of which is associated with a part which is fixed with respect to said carriage for bringing about a movement of said carriage relative to said other wheel, and means yieldably mounting said follower member upon said fixed part and adapted to permit yielding of said follower member with respect to said cam member upon the resistance to movement of said carriage exceeding a predetermined extent.
- 80 14. In apparatus of the character described, in combination, a pair of abrasive wheels, means for holding work between and in operative relation to said wheels, a carriage rotatably supporting one of said wheels and adapted to be moved relative to the other of said wheels, a cam member and a follower member, one of which is associated with said carriage and the other of which is associated with a part which is fixed with respect to said carriage for bringing about a movement of said carriage relative to said other wheel, and means yieldably mounting said follower member upon said fixed part and adapted to permit yielding of said follower member with respect to said cam member upon the resistance to movement of said carriage exceeding a predetermined extent.

action thereon by said wheels, a carriage 5 rotatably supporting one of said wheels and adapted to be moved relative to the other of said wheels, a cam member and a follower member, one of which is associated with said carriage and the other of which is associated with a part which is fixed with respect to said carriage for bringing about a movement of said carriage relative to said 10 other wheel, an arm supporting at one end thereof one of said members and pivotally supported at the other end thereof upon said fixed part, and yieldable means preventing movement of said arm about its pivotal support.

15. In apparatus of the character described, in combination, a pair of abrasive wheels, means for holding therebetween work for action thereon by said wheels, a carriage 20 rotatably supporting one of said wheels and adapted to be moved relative to the other of said wheels, a cam member mounted upon said carriage, a follower member mounted upon a part which is fixed relative to said 25 carriage, and means for adjusting said cam member relative to said carriage to adjust the distance between said two wheels.

16. In apparatus of the character described, in combination, a pair of abrasive wheels, 30 means for holding therebetween work for action thereon by said wheels, a carriage rotatably supporting one of said wheels and adapted to be moved relative to the other of said wheels, a cam member mounted upon 35 said carriage, a follower member mounted upon a part which is fixed relative to said carriage, and means for adjustably positioning said follower member to adjust the distance between said two wheels.

40 17. In apparatus of the character described, in combination, a pair of abrasive wheels, means for holding therebetween work for action thereon by said wheels, a carriage rotatably supporting one of said wheels and 45 adapted to be moved relative to the other of said wheels, means for moving said carriage relative to one of said wheels comprising a cam member and a follower member, one of which is associated with said 50 carriage and the other of which is associated with a part which is fixed with respect to said carriage, and means forming an operative connection between said carriage and its associated member including a lost motion connection.

55 18. In apparatus of the character described, in combination, a pair of abrasive wheels, means for holding therebetween work for action thereon by said wheels, a carriage 60 rotatably supporting one of said wheels and adapted to be moved relative to the other of said wheels, a rotatable shaft carried by said movable carriage, a cam member rotatable with but slidable with respect to 65 said shaft, a follower member associated

with a part which is fixed with respect to said carriage, and means for adjustably positioning said cam member along said shaft.

19. In apparatus of the character described, in combination, a pair of abrasive wheels, 70 means for holding therebetween work for action thereon by said wheels, a carriage rotatably supporting one of said wheels and adapted to be moved relative to the other of said wheels, a rotatable shaft carried 75 by said movable carriage, a cam member rotatable with but slidable with respect to said shaft, a follower member associated with a part which is fixed with respect to said carriage, and means for predetermining the 80 extent of slidable movement of said cam member relative to said shaft.

20. In apparatus of the character described, in combination, a pair of abrasive wheels, 85 means for holding work between and in operative relation to said wheels, power driven means for moving one wheel relative to the other, means for adjusting said one wheel toward or away from the other, and means for making inoperative one of said last 90 mentioned means thereby to permit operation of the other.

21. In apparatus of the character described, in combination, a carrier adapted to support for free lateral movement thereon work 95 of round section, an abrasive wheel on one side of said carrier for action upon the work thereon, a second abrasive wheel on the other side of said carrier for action on the work thereon, said wheels being adapted to effect 100 simultaneous rotation and grinding of work on said carrier and to effect a feeding movement thereof lengthwise of said carrier, means for limiting movement of the work lengthwise of said carrier, and means for 105 withdrawing one of said wheels from the other to release the work therebetween.

22. In apparatus of the character described, in combination, a carrier adapted to support for free lateral movement thereon 110 work of round section, an abrasive wheel on one side of said carrier for action upon the work thereon, a second abrasive wheel on the other side of said carrier for action on the work thereon, means for giving one of said wheels a linear movement lengthwise of said carrier, means for preventing movement of the work lengthwise of said carrier during action thereon by said wheels, and means for withdrawing one of said wheels from the 115 other to release the work therebetween.

23. In apparatus of the character described, in combination, a grinding wheel adapted to be rotated at relatively high speed, a regulating wheel adapted to be rotated at 125 relatively low speed, said wheels being rotated to present adjacent operative surfaces traveling in opposite directions, means for holding work of round section between said wheels for grinding action thereon by said 130

grinding wheel and rotating action thereon by said regulating wheel, means for giving said grinding wheel a linear movement lengthwise of said carrier, means for preventing movement of the work lengthwise of said carrier during movement of said grinding wheel, and means for withdrawing one of said wheels from the other to release the work therebetween.

- 10 24. In apparatus of the character described, in combination, a grinding wheel adapted to be rotated at relatively high speed, a regulating wheel adapted to be rotated at relatively low speed, said wheels being rotated to present adjacent operative surfaces traveling in opposite directions, means for holding work of round section between said wheels for grinding action thereon by said grinding wheel and rotating action thereon 15 by said regulating wheel, a stop positioned in the path of travel of work along said work-holding means, the path of travel of the operative surface of said regulating wheel being inclined with respect to the path of travel 20 of the work along said carrier, thereby to hold the work against said stop, and means for withdrawing one of said wheels from the other to release the work therebetween.

25. In apparatus of the character described, in combination, a grinding wheel adapted to be rotated at relatively high speed, a regulating wheel adapted to be rotated at relatively low speed, said wheels being rotated to present adjacent operative surfaces 30 traveling in opposite directions, means for holding work of round section between said wheels for grinding action thereon by said grinding wheel and rotating action thereon by said regulating wheel, a stop positioned 35 in the path of travel of work along said work-holding means, the path of travel of the operative surface of said regulating wheel being inclined with respect to the path of travel of the work along said carrier, thereby 40 to hold the work against said stop, means for giving said grinding wheel a reciprocating movement relative to the work, and means for withdrawing one of said wheels from the other to release the work therebetween.

- rotated at a relatively low speed and in a direction to present an operative surface traveling in a direction opposite from that of the adjacent grinding wheel surface, and the 5 third of which members includes a member for holding work of round section in operative relation to said two wheels, supporting means for one of said members adapted to permit movement thereof toward or away 10 from one of the remaining members; power actuated means for moving said supporting means; manual means for moving said supporting means, a detachable connection between said power actuated means and said 15 supporting means, and a detachable connection between said manual means and said supporting means. 20
31. In a centerless grinder the combination of a work support having an end stop to position the work; a grinding wheel arranged to shift back and forth in the direction of its axis during the grinding operation; and a regulating wheel skewed to exert on the work an axial feeding tendency in the direction of 25 said end stop. 25
32. In apparatus of the character described, in combination, a grinding wheel adapted to be rotated at a relatively high speed, a regulating wheel adapted to be rotated at a relatively low speed, said regulating wheel being rotated to present an operative surface traveling relative to that of said grinding wheel to control the rotation of round work, a carrier for supporting work of round 30 section in operative relation to the operative surface of said wheels, means for giving said grinding wheel a movement in the general direction in which said carrier extends, and means for limiting the movement of the work 35 along said carrier whereby movement of said grinding wheel is prevented from moving the work lengthwise of said carrier. 40
33. In apparatus of the character described, in combination, a carrier for supporting thereon work of round section, a grinding wheel positioned on one side of said carrier and rotatable at a relatively high speed, thereby to perform a grinding operation upon said work, a regulating wheel positioned on the other side of said carrier and rotatable at a relatively low speed, thereby to control the rotation of said work on said carrier, means for giving said grinding wheel a linear movement relative to the work, and a 50 stop for engaging the work on said carrier, the path of travel of the operative surface of said regulating wheel being inclined with respect to the path of travel of the work on said carrier, whereby said regulating wheel is effective to hold said work against said stop during the travel of said grinding wheel. 55
34. In apparatus of the character described, in combination, a carrier for supporting thereon work of round section, and 60 provided with a stop for engagement with the work, a grinding wheel positioned on one side of said carrier for performing a grinding operation upon said work, means for moving said grinding wheel longitudinally of said carrier, and means for simultaneously controlling the rotation of said work on said carrier and holding said work against said stop during the movement of said grinding wheel. 65
- In testimony whereof, I have signed my name to this specification this first day of October, 1923. 70
